UNITED STATES PATENT OFFICE

154,515

DESIGN FOR A TABLE

Lester Sejarto, Richmond Hill, N. Y.

Application December 30, 1947, Serial No. 143,428

Term of patent 14 years

(Cl. D33—14)

To all whom it may concern:

Be it known that I, Lester Sejarto, a citizen of the United States, residing at Richmond Hill, in the county of Queens, city and State of New York, have invented a new, original, and ornamental Design for Table, of which the following is a specification, reference being had to the accompanying drawing, forming part thereof, in which

Fig. 1 is a front elevational view of a table, showing my new design;

Fig. 2 is a top plan view thereof; and

Fig. 3 is a perspective corner view thereof.

I claim:

The ornamental design for a table, as shown,
LESTER SEJARTO.
